PICKER SPINDLE

Filed Dec. 5, 1929

UNITED STATES PATENT OFFICE

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

PICKER SPINDLE

Application filed December 5, 1929. Serial No. 411,941.

This invention relates to picker spindles for looms and it is the general object of the invention to provide means whereby expansion of the spindle will not interfere with the proper holding or aligning of the same.

In box looms and on the plain ends of certain types of automatic looms it is customary to employ a picker spindle or rod along which a rawhide picker slides. It is usual to mount the spindle behind the reed line and hold the same securely in stands or extensions supported by the lay end. During the operation of the loom considerable heat is likely to develop as a result of the fractional sliding of the picker along the spindle, causing the latter to expand. The resultant strain is likely to break or bend the spindle so as to adversely influence the delivery of the shuttle from the box. It is an important object of my present invention to provide telescoping members each of which may be tightly clamped to the lay but so arranged that expansion may take place without straining either the lay end or the spindle parts.

It is a further object of my present invention to secure one end of a tubular element to the lay end and slide therein a rod element having one end connected at the opposite end of the lay end, both of these elements being held very tightly in position but each having a free end so that any longitudinal expansion may be provided for without bending the spindle.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a top plan view of one end of a lay having my invention applied thereto,

Fig. 2 is a rear elevation of the structure shown in Fig. 1 showing my invention applied thereto,

Fig. 3 is an enlarged section taken on line 3—3 of Fig. 1,

Fig. 4 is a vertical section on line 4—4 of Fig. 3; and

Fig. 5 is a vertical section on line 5—5 of Fig. 3.

Referring to Figs. 1 and 2 I have shown a lay 10 having a rear wall 11 and supported by a sword 12. Box guides 13 receive tongues 14 of a set of shifting boxes 15. A stand 16 at the outer end of the lay may be held thereto by means of a bolt 17, while at the inner end the lay end may be provided with a lug or boss 18. A picker 19 extends through the back wall 11 and has engagement with the shuttle S, being propelled by the picker stick 20.

Except for the form of the stand 16 and lug 18, the matter thus far described is of common construction, the boxes 15 moving vertically between the guides 13 and the picker 19 being moved to the right from the position shown in Fig. 1 to throw the shuttle to the opposite side of the loom.

In carrying my present invention into effect I provide a picker spindle designated generally at 30 and comprising an outer tubular element 31 which as shown herein may extend through the stand 16. As shown in Fig. 4 said stand is split as at 32 and has extending therethrough a clamping screw 33. The latter when screwed tightly into position holds the left end of the tubular element firmly in fixed position with respect to the stand 16 and therefore the lay.

Extending through the tubular element is a reinforcing rod 34 secured in the lug 18 in a manner similar to that in which the tubular element is held in position. The lug is split as at 35 and the clamping screw 36 is threaded into the lower part of the lug, being effective to draw the upper portion thereof down into clamping relation with respect to the rod. Each of the constituent parts of the spindle 30 is adjustable longitudinally in its own support and the rod 34 is made of such size as to fit the interior of the tubular element.

In operation, the picker 19 will slide along the tubular element and the latter will be supported at the outer end by the stand 16 and at the inner end by the rod 34 and its supporting lug 18. As weaving continues and the rod gets warm, expansion of the tubular element in a linear direction can take place freely in-

asmuch as the right end of said element is spaced a short distance from the stud 18. In a similar manner any heat which may be communicated to the rod to cause expansion thereof will not result in straining or bowing of the rod or the surrounding tubular element, because of the fact that the left end of said rod is free.

From the foregoing it will be seen that I have provided a pair of telescoping elements each of which has a free end and each of which has an end securely fastened to the lay so that expansion of each element may take place without causing bending or straining of the spindle. Furthermore, the rod reinforces the tubular element.

Having thus described my invention it will be seen that changes and modifications may be made therein by those skilled in the art without departing from the spirit and scope of the invention and I do not wish to be limited to the details herein disclosed, but what I claim is:

1. In a picker spindle for a loom having a picker movable along the lay, a pair of spaced supports, and a pair of telescoping picker spindle forming elements extending along the path of travel of the picker, each element having one end secured to a support and having the other end free to move independently of the other element when expanded by heat.

2. In a picker spindle for a loom having a picker movable along the lay, a pair of spaced supports, a pair of telescoping elements extending through the picker one of which has one end secured to one support and the other of which has an end secured in the other support, one element being slidably freely within the other and independently thereof.

3. In a picker spindle for a loom having a picker movable along the lay, a pair of spaced supports, a tubular spindle forming element secured to one support and extending through the picker, a second spindle forming element located within the tubular element and secured to the other support, each element having a free end which is movable independently of the other.

4. In a picker spindle for a loom having a picker movable along the lay, a pair of spaced supports, and a pair of picker spindle forming elements, one of said elements being held by one support and having direct engagement with the picker and the other element lying within the first element and reinforcing the same, one end of the latter element being held to the other support, each element having a free end movable independently of the other element.

5. In a picker spindle for a loom having a picker movable along the lay, a pair of telescoping spindle forming elements extending along the path of travel of the picker each of which is held at one end to the lay and is

free at the other end to move independently of the other element.

6. In a picker spindle for a loom having a picker movable along the lay, a pair of spindle forming members substantially parallel to the lay and to each other and extending through the picker, and a pair of supports, one for each end of the spindle, one member having one end thereof secured to one support and the other member having the end thereof remote from said one support secured to the other support, each member having a free end which is movable independently of the other member when expanding due to heat.

7. In a loom, a picker spindle comprising an outer tubular picker supporting member, an inner member which has telescoping engagement with the tubular member to brace the latter, a support for each member, each member being movable longitudinally in its respective support whereby each member may move along and independently of a movement of the other member.

In testimony whereof, I have hereunto affixed my signature.

RICHARD G. TURNER.
